UNITED STATES PATENT OFFICE.

MYRON FISH, OF CENTRAL FALLS, RHODE ISLAND.

BRUSHING-MACHINE FOR LOOM-HARNESS.

No. 900,994.

Specification of Letters Patent.

Patented Oct. 13, 1908.

Application filed June 18, 1906. Serial No. 322,349.

To all whom it may concern:

Be it known that I, MYRON FISH, a citizen of the United States, residing at Central Falls, in the county of Providence and State of Rhode Island, have invented certain new and useful Improvements in Brushing-Machines for Loom-Harness, of which the following is a specification.

My invention relates to improvements in brushing machines for loom harnesses, and the object of my invention is to provide a brushing machine in which paired revolving brushes are provided with a reciprocating movement and also made to alternately approach and separate from each other by an opening and closing movement, so that the fiber of the harness is always brushed in the same direction regardless of the speed at which the brushes revolve. I accomplish this object by the mechanism shown in the accompanying drawings in which

Figure 1 is a vertical section of the machine through line X—X of Fig. 3. Fig. 2 is a plan view of the machine. Fig. 3 is a vertical front elevation. Fig. 4 is a detail of the adjusting mechanism. Fig. 5 is a detail view of portions of the device illustrating more fully the brush operating and adjusting mechanism. Fig. 6 is a view of the cam detached.

In Fig. 1, A is the supporting frame of the machine. B, is a horizontal member securely fastened to the frame and provided with a vertical slot S in which a crank pin m' operates. b—b are stay rods fixed in the frame A—A, and the member B; C—C are rollers which rotate freely upon the stay rods b—b; these rollers C—C are flanged, and upon them is supported the members D—D' D''—D'' of a reciprocating carriage which consists of the members D—D' D''—D'' seen best in Fig. 2, these three members being braced and rigidly united by suitable stay bolts d—d'. From the members D—D' D''—D'' of the reciprocating carriage, two arms D—D' project upwardly forming the supports for the quadrant brush arms E—E', one pair of which arms is situated on each side of the machine; the upper pair supports the upper revolving brush F' by the shaft f while the lower pair supports the lower brush F in like manner. These quadrant arms E—E' are sleeved on shafts d—d'' carried by the arms D—D', and integral with E—E' are quadrant gears e—e' meshing with each other.

G, Fig. 2, is the driving pulley having a long hub g' upon which are mounted the gears 1 and 5; from 1, motion is communicated by the trains of gears 1—2—3—4, 1'—2'—3'—4', to the revolving brushes F—F'. Gear 5 through the medium of gear 6 also drives the shaft M on which is mounted the crank m, Fig. 1, the shaft being journaled through the members D—D', D''—D''. This crank is slotted for the adjustment of the crank pin m' as shown at m'' in Fig. 1, which operates in the slot S of the member B. N is a cam fixed upon the shaft M and provided with a slot n, and communicating reciprocating motion by means of the bell crank O—O', the rock shaft d'' on which said bell crank O'—O' is fixed, and the quadrant gears e—e', to the arms E—E'. The channel n in the cam N is concentric with the shaft M for nearly one-half of its course and also concentric with the shaft M through nearly the other half of its course, one of the concentric courses being of a greater radius than the other course, the terminals of the courses being united by relatively curved portions as shown at n' in Fig. 6. By this means as the shaft M is rotated the roller o' of the crank arm O—O' will be caused to travel nearly one-half of its course in one position, and then suddenly be moved outward or inward, as the case may be, and travel the remainder of its course in that position. Thus as the cam rotates the brushes F—F' will operate close to the harness during the movement of the carriage frame in one direction, and be thrown outward away from the harness during the return movement of the carriage, as will be obvious. H is the harness upon which the brushes operate. The driving pulley and the various gears, as well as the brushes with their supporting arms, including the bell crank lever O—O' and the cam N, are supported by and movable with the carriage D—D'—D''. The shaft M is connected by a universal joint M' with a worm and gear on the end of the frame work of the machine to operate a feed-motion for feeding the harness through the machine. This mechanism is not shown, since any suitable feed-motion may be used to feed the harness regularly through the machine.

The pressure of the brushes F—F' upon the harness is adjusted by the device shown at the top of Fig. 1, and more in detail in Fig. 4. Between the two upper arms E—E' and firmly attached to these arms is a bar P.

shown in section in Fig. 1 and having a lug p slotted at p' as shown. The portion O' of the bell crank is forked at its outer end and provided with a vertical screw Q turning 5 freely in the limbs of said fork being held therein by nut q . The screw Q is provided with a nut q having radial pins $r-r'$ fixed thereon. These pins engage the slot p' in the lug p , and as the screw Q is turned the 10 arms $E'-E'$ are raised or lowered with reference to the member O' of the bell crank, while $E-E$ are simultaneously moved in an opposite direction, and thus through the 15 quadrant gears $e-e'$ the distance between F' and F is varied at will. This adjustment also allows the wear on the brushes $F'-F$ to be taken up as occasion requires.

In Fig. 2, 3, is shown rolls u for applying varnish, oil or whatever substance or pigment it may be desired to apply to the harness. The lowermost roll u operates in a pan U containing the substance to be applied to the harness. In these views is also seen a pair of rollers 6^x disposed between the rolls u and the brushes F, F' , the function of which is to remove any surplus dressing applied by the rolls u . The rolls 6^x may be driven in any suitable or desired manner from the rolls u which it is not believed necessary to illustrate, as, it will be obvious that the rolls 6^x may be dispensed with without in any manner interfering with the operation of the device. As illustrated in Fig. 2, the rolls u are driven by gears $4^x, 5^x$, the former 30 mounted on a shaft (not shown) which carries a pulley 3^x to receive a drive belt 2^x .

An endless chain w , is operated by the machine and embodies two series of hooks W one series on each side of the frame (see 40 Figs. 1 and 2). The harness fibers or strings are carried by these hooks W of the chain w , and are kept tight by the tension of the tension lever A^x (Fig. 1). The two arms a^2, a^3 of this lever are separate, and are geared 45 (not shown) in the same manner as the arms E, E' , so that the top or upper ends thereof move outwardly as the lower end of the tension lever A^x is pulled by the coil spring A^{xx} .

When the harness is affixed to the endless 50 chain w and motion communicated to the latter, the harness strings are drawn between the rollers u which applies the varnish, oil, or other substance thereto, the rolls 6^x removing any surplus substance prior to the 55 harness reaching the brushes F, F' which latter act upon the harness to impart the desired finish thereto. The operator removes the finished harness as the same emerges from the brushes F, F' and adds the harness 60 to the chain on the opposite side of the machine without stopping the latter.

It will be seen from the drawings that the bristles upon the brushes $F-F'$ are not uniformly distributed over the cylinders but are 65 arranged in a series of strips, parallel with

the axes of the two cylinders. The reason for this is that in practice I have found that a superior finish is given to the harness by allowing the successive strips of bristles on one cylinder to alternate with those upon the 70 other cylinder in their contact with the harness, as shown in Fig. 1; that is, the harness is not touched by the bristles of the lower cylinder at the instant it is being brushed by those of the upper cylinder; but strips of the 75 bristles of the upper cylinder alternate with those of the lower cylinder in their contact with the harness thus giving a more yielding contact than would be the case if the bristles worked in direct opposition to each other. The alternation of the strips of bristles is maintained by the respective trains of gears $1-2-3, 1'-2'-3'$, etc.

As the driving pulley revolves it also causes the revolution of the cam N and the 85 shaft M to which is attached the crank m with the crank pin m' . As the member B is fixed the revolution of the shaft M causes the reciprocation of the carriage $D-D, D'-D'$ by means of the slot S and the crank and 90 crank pin $m-m'$. The various members attached to the carriage $D-D, D'-D'$, etc., that is to say, the uprights D^2-D^4 , the quadrant arms $E-E'$ and the revolving brushes $F-F'$, with their respective trains 95 of gears reciprocate simultaneously with the carriage $D-D, D'-D'$.

By means of the symmetrical cam N , the bell crank $O-O'$ and the quadrant gears $e-e'$, the revolving brushes $F-F'$ are made 100 to come together abruptly at the beginning of one movement of the carriage $D-D$, and to separate abruptly at the end of that movement so that the harness is brushed only in one direction by the brushes regardless of the 105 speed of their revolution.

By means of the endless chain w the brushing process is continuous, the harness passing side wise through between the brushes, permitting the operator to remove the finished harness as it emerges, and add the unfinished harness upon the opposite side without stopping the machine.

Having now described my invention what I claim and desire to secure by Letters Patent is:

1. In a machine for brushing loom harnesses, paired cylindrical brushes revolving on opposite sides of the harness; a carriage supporting said brushes; a shaft revolubly attached to said carriage and provided with a crank and crank pin; a member rigidly fixed to the frame of the machine and having a slot engaging said crank pin so that the revolution of said shaft by means of said crank, crank pin, and slot, imparts a reciprocating motion to the carriage aforesaid substantially as described.

2. In a harness brushing machine paired cylindrical brushes revolving on opposite 130

sides of the harness, paired arms pivoted at one end and supporting said brushes at the other; quadrant gears integral with said arms and operating to change the distance 5 between said cylindrical brushes; a bell crank pivoted upon the same shaft with the upper pair of said arms, and having one of its ends adjustably attached to said upper pair of arms; and a revoluble cam engaging 10 the other end of said bell crank, all substantially as set forth for the purpose specified.

3. In a harness brushing machine, revolving paired cylindrical brushes arranged one above the other, and provided with a series 15 of strips of bristles parallel to the axes of said cylinders; an upper and a lower pair of horizontal arms supporting the upper and lower cylindrical brushes respectively; an upper and a lower train of gears mounted respectively 20 on said upper, and on said lower arms, and operating the upper and lower cylinder respectively, the two gears in each train farthest from the cylinders being in mesh with each other; and means for driving said 25 gears; the relation of gears, cylinders and strips of bristles being such that a given strip of bristles on one cylinder will always come in contact with the harness at a point between adjacent strips of bristles on the opposite 30 cylinder substantially as described.

4. In a harness brushing machine of the type described, means for adjusting the distance between the cylinders, consisting of a bar connecting the arms supporting the upper cylinder and provided with a slotted lug fixed thereon; a bell crank engaging said bar and Y shaped at its outer end, the space between the ends of the Y being greater than the width of said lug and encircling the same; 40 a bolt or screw passing through the ends of said Y and having a nut thereon provided with opposed radially projecting pins adapted to engage the slot in said lug; said instrumentalities operating to vary at will the re-

spective positions of the bell crank and arms 45 aforesaid substantially as set forth.

5. In a machine for brushing loom harnesses, paired revolving brushes acting on opposite sides of the harness; a pair of horizontal quadrant arms pivoted at one end 50 upon a horizontal shaft and supporting at the opposite end the upper revolving brush; a like pair of horizontal arms supporting the lower brush and pivoted upon a second shaft; each pair of said arms being provided with a 55 quadrant gear integral therewith, said gears meshing with each other; a train of gears supported upon one of said upper arms, and a like train supported by the adjacent lower arm, said gears operating to revolve said 60 brushes and to cause the same to maintain a fixed relation to each other; a bell crank adjustably connected at one end with one pair of said horizontal arms; a cam engaging the other end of said bell crank and causing 65 said brushes to alternately approach and separate from each other; a horizontal reciprocating carriage supporting said arms, bell crank, shafts and brushes; a horizontal driving shaft revolvably mounted on said carriage 70 and having fixed thereon the cam aforesaid and provided with a crank and crank pin; a suitable supporting frame for said carriage, having fixed thereon a member provided with a vertical slot engaging said crank pin, 75 and operating to impart a reciprocating movement to said carriage by the revolution of said driving shaft; and means for adjusting the distance between said paired brushes substantially as described for the purpose 80 specified.

In testimony whereof I affix my signature in presence of two witnesses.
